UNITED STATES PATENT OFFICE.

JOHN P. HUBER, OF ST. LOUIS, MISSOURI.

VEHICLE-SEAT.

SPECIFICATION forming part of Letters Patent No. 475,083, dated May 17, 1892.

Application filed February 11, 1892. Serial No. 421,103. (No model.)

To all whom it may concern:

Be it known that I, JOHN P. HUBER, of the city of St. Louis and State of Missouri, have invented certain new and useful Improvements in Vehicle-Seats, of which the following is a full, clear, and exact description, reference being had to the accompanying drawings, forming a part hereof.

My invention relates to improvements in vehicle-seats; and it consists in the novel arrangement and combination of parts, as will be more fully hereinafter described, and designated in the claims.

In the drawings, Figure 1 is a perspective view of my complete invention, showing the same attached to the ordinary seat of a vehicle and in a position to be used. Fig. 2 is a plan view showing the back of the seat in a folded position. Fig. 3 is a perspective view in detail, showing the manner of securing the back to the seat or casting secured to the same. Fig. 4 is a side elevation of the arms employed, to which the foot-rest is attached, and showing the manner in which the same are secured to the seat. Fig. 5 is a longitudinal section taken on the line $x-x$ of Fig. 5, but somewhat enlarged in order to show more clearly the parts employed for effecting a movable connection; and Fig. 7 is a perspective view of the shaft which I employ in attaching the arms for the foot-rest to the casting carried by the seat.

My present invention consists of improvements over my pending application, filed November 10, 1891, Serial No. 411,453.

The improvements consist, essentially, of a detachable back for the seat, which may be removed from the said seat when the same is not desired to be used, and, further, with the foot-rest which is movably secured to the seat and which may be folded upon the same or entirely detached from the said seat when so desired.

Referring to the drawings, 1 represents a buggy-seat, which is of the ordinary construction and to which my invention is easily applied. In order that my invention may be removably attached to said seat, a staple 2 is secured to the upper surface of said seat in

any suitable manner, and near the edge of said seat is a cleat 3, and opposite said cleat and at a suitable distance therefrom is also secured to the seat a turn-clamp 4, between which cleat and clamp the stationary plate 5 of the seat is adapted to be clamped after the end of the same has been inserted into the staple 2, as shown in Fig. 1 of the drawings. By turning the clamp 4 in a position opposite to that shown in Fig. 1 plate 5, and consequently the seat, may be entirely removed from the vehicle-seat.

6 represents a second plate, which is united to the plate 5 by means of a hinge 7, constituting a movable connection and allowing the plate 6 to be turned back upon said plate 5 when it is desired to fold the seat in a compact position.

8 represents an additional seat, which is secured in any suitable manner to the arm 6, and to the under surface of said seat is secured a hinged leg 9, which is adapted to be moved only toward the plate 6 in folding the same. Said leg 9 is composed of two parts and is adjustable to any length, the upper portion 10 of which is provided with a vertical opening and the lower portion 11 provided with a rounded extension 12, which is adapted to freely move or slide in said opening formed in the portion 10, and by the manipulation of the hand-screw 13 the said leg 9 will be made adjustable. The lower end of the leg 9 is pointed and said end adapted to be inserted into a suitable opening formed in a plate 14, which is secured to the bottom or floor of the vehicle-body, as shown in Fig. 1.

15 represents a curved brace which partially constitutes the back of the seat 8 and which is preferably made of metal, suitably shaped and finished, and the same covered with leather or upholstering, as may be desirable. To the said brace 15 are secured four plates 16, which are provided with suitable openings, to which the hinged supports for the rest or back of the seat 8 are attached.

17 represents the rear support, which is V-shaped, the ends of which are secured to two of the plates 6 at the rear of the brace 15, forming a movable connection between said brace and support. The brace 17 is also provided with a depression 18 where the same is united with the plate 6, and said depression

is of a length corresponding to the width of said plate, and when the parts are united, as shown in Fig. 1, and a bolt 19 passed through said portion of the support and the plate 6 5 the part will be rigidly united. The ends of the brace 15 are also provided with supports 20, which are attached to the brace 15 in a similar manner, and the free ends of said arms formed into hook-shaped extensions 21, 10 which are adapted to be passed into suitable openings formed for their reception in the casting carried by the under surface of the seat 8, forming a rigid connection between said arms or braces and the seat when the 15 parts are united. The said arms are also provided with elongated openings 22 near the hinged ends of the same, through which a strap 23 is adapted to be passed in order to prevent the child from falling out or off of 20 said seat 8.

In applying the back of the seat the hooked ends of the supports 20 are first inserted into the openings formed in the casting, after which the rear support is attached to the plate 25 6 by means of a bolt, as already described.

24 represents a casting, which is secured to the front under surface of the seat 8, and said casting provided with four ears 25, which are arranged in pairs, by means of which the foot- 30 rest is movably secured to the bottom of the seat. Said casting 24 also projects a suitable distance beyond the sides of the seat 8 and said projecting ends of the casting provided with elongated openings 26, which are adapted 35 to receive the hooked ends 21 of the supports 20, as best shown in Fig. 3 of the drawings. The ears 25 are each provided with circular openings 27, which are in alignment with one another, through which a shaft 28 40 is adapted to be passed and turned. The ears 25 (to the right looking at Fig. 5) are each provided with extensions 29, as best shown in Fig. 6, allowing sufficient space for the lugs 30, carried by the shaft 28, to pass in uniting 45 the several parts, as hereinafter described.

31 represents two arms, the upper ends of which are provided with horizontal extensions 32, and said extensions provided with elongated openings 33, the terminations of which 50 are enlarged in order to allow the rounded portions of the shaft 28 to freely turn in said openings when it is desired to attach or remove the arms 31, and consequently the foot-rest, from the seat 8. The lower ends of the 55 arms 31 are provided with supports 34, upon which the foot-rest 35 is adapted to come in contact when the said rest is in the position shown in Fig. 1. The under surface of the foot-rest 35 is provided with two plates 36, 60 which are secured to the same in any mechanical manner, and the perforated portions or ends of said plates projecting a suitable distance beyond the rear edge of the same for allowing a shaft or rod 37 to be passed 65 through the said plates and also through suitable openings formed in the lower ends of

the arms 31, forming a movable connection between said rest and arms and allowing the said rest to be folded in a position shown in Fig. 4. When the arms 31 are in the position 70 shown in Fig. 4, the upper surfaces of the horizontal extensions 32 of said arms will come in contact with the lower surface of the casting 24, and therefore hold the said arms in the proper angle. 75

38 represent extensions formed with the plates 36 and are adapted to come in contact with the rests or supports 34 when the rest 35 is in position, as shown in Fig. 1, to be used. 80

The shaft which I employ for attaching the arms of the foot-rest to the casting carried by the seat 8 is especially constructed for the purpose, the construction and manipulation of which I shall now proceed to describe. The said shaft 28 is round in cross-section, and one end of the same is somewhat flattened, providing means for turning and manipulating the same. The lugs 30, formed on said shaft, are a suitable distance apart but of such a distance as to correspond to the distance between the ears 25, formed with the casting 24, in order that the said shaft may be turned after the same has been inserted in a position, as shown in Fig. 5. The said shaft 21 is also provided with cut-away portions 39, which are located a suitable distance apart, the length of which corresponds to the distance between the two pairs of lugs 25, which when the cut-away portions of said shaft are in said position, the slots 33 being of a corresponding width to said portions of the shaft, will allow the horizontal portions 32 of the arms 31 to be moved for folding the said arms. 90 95

When it is desired to unite the arms 31 to the casting 24, the enlarged portions or terminal ends of the slots 33, formed in the horizontal extensions 32 of the same, must necessarily be in alignment with the openings formed in the ears 25, as shown in Fig. 6, allowing the rounded portion of the shaft 38 to freely move in said openings formed in the ears and also through the enlarged portions of the slots 33. The shaft 28 on being completely inserted in said openings and partially turned the said arms 34 will be firmly locked to the casting 24 and also the said shaft prevented from moving out of said opening. In other words, the cut-away portions 39 of the shaft allow the extensions 32 of the arms to 100 be moved when the said shaft is in its proper position; but when the said shaft is slightly turned the widest portion of the said shaft being wider than the narrowest portions of the slots 33 prevents the said extensions 32 105 from being moved in a horizontal direction. 110 115

When it is not desired to use the seat 8 and its parts, the entire mechanism may be detached from the seat 1 by the proper manipulation of the clamp 4; or, if desired, the rest or back for the seat 8 may be removed from the same, and also the foot-rest and the seat 120 125 130

8 be folded upon itself and the detachable parts—namely, the back for the seat and the foot-rest—placed in any convenient portion of the vehicle.

5 From the foregoing description it will be seen that the parts composing my invention are all detachable, or said parts may be folded upon one another without detaching the parts, as may be deemed desirable.

10 Having fully described my invention, what I claim is—

1. A vehicle-seat adapted to be folded upon itself and a back or rest adapted to be removably attached to the same, substantially as described.

15 2. A vehicle-seat mounted upon a folding support, a back or rest removably secured to the same, and a foot-rest also removably secured to said seat and adapted to be folded, substantially as described.

20 3. A vehicle-seat comprising a back or rest, a brace 15 of suitable shape, supports hinged to the same, the opposite ends of which are adapted to be removably secured to said seat, and a folding step also attached to the said seat, substantially as described.

25 4. A vehicle-seat consisting of a back or rest, supports hinged to the same, the center one of which is secured to the said seat by means 30 of a suitable bolt, hooks formed on the ends of the end supports for said brace and adapted to be inserted in suitable openings formed in the casting 24, secured to said seat, and a foot-rest adapted to be secured to said casting by 35 means of a removable bolt or shaft by properly manipulating the same, substantially as described.

35 5. A vehicle-seat consisting of a back or rest adapted to be removably attached to the same, 40 a foot-rest having arms 31, a casting 24, secured to the under surface of said seat and provided with ears 25, a bolt, such as 28, adapted to be passed through said ears and arms, and slots, such as 33, formed in the extension 32 of said arms for allowing the same

45 to be moved in a horizontal direction for folding, substantially as described.

6. A vehicle-seat having a foot-rest and a bolt, such as 28, provided with cut-away portions 39 and lugs 30 for locking said bolt and 50 allowing the said rest to be turned or folded, substantially as described.

7. A vehicle-seat having a casting 24 attached to the under surface of the seat, ears 25, formed with the same, holes formed in the 55 said ears, arms, such as 31, provided with horizontal extensions 32, slots 33, formed in the said extensions, the terminations of which are enlarged, a shaft, such as 28, provided with cut-away portions 39 and lugs 30, adapted to 60 be passed through said openings formed in the ears and through the said slots 33, and a foot-rest, such as 35, hinged to the lower ends of the said arms and adapted to rest upon suitable supports 34, formed on the lower ends 65 of said arms, substantially as described.

8. A vehicle-seat consisting of a back or rest, a casting 24, adapted to be secured to the under surface of the said seat, the ends of which extend beyond the same, openings, such as 26, 70 formed in the said extensions, providing means for securing the said back to the seat, ears 25, formed with the said casting and provided with openings 27, extensions, such as 29, formed in two of the said ears, supports, such 75 as 31, having horizontal extensions 32, elongated openings, such as 33, formed in the said extension, the terminations of which are enlarged, a shaft 28, having cut-away portions, such as 39, and lugs 30, and a foot-rest, such 80 as 35, movably secured to the lower end of said arm and adapted to rest upon suitable supports formed with the said arms, substantially as described.

In testimony whereof I affix my signature in 85 presence of two witnesses.

JOHN P. HUBER.
